(57) **CLAIM**

The ornamental design for an tool and chain holder, as shown and described.

DESCRIPTION

FIG. 1 is a Top plan view of the tool and chain holder; FIG. 2 is a Front elevation view of the tool and chain holder thereof;

FIG. 3 is a Bottom plan view of the tool and chain holder thereof;

FIG. 4 is a Right Side elevation view of the tool and chain holder thereof;

FIG. 5 is a Left Side elevation view of the tool and chain holder thereof;

FIG. 6 is a Front Top isometric view of the tool and chain holder thereof;

FIG. 7 is a Back Top isometric view of the tool and chain holder thereof; and,

FIG. 8 is a Back Top isometric view of the tool and chain holder thereof showing a ROPS bar and seat arrangement. The dotted lines in FIG. 8 represent the environment and form no part of the claimed design.

1 Claim, 3 Drawing Sheets
